W. A. COOK ET AL.
DENOMINATING APPARATUS.
FILED MAR. 9, 1921.

1,444,586.

UNITED STATES PATENT OFFICE.

WILLIAM A. COOK, OF HOLLIS, AND JOSEPH LEVINE, OF BROOKLYN, NEW YORK,
ASSIGNORS TO THE DENOMINATOR ADDING MACHINE COMPANY, OF BROOKLYN, NEW YORK, A CORPORATION OF NEW YORK.

DENOMINATING APPARATUS.

Application filed March 9, 1921. Serial No. 450,900.

To all whom it may concern:

Be it known that we, WILLIAM A. COOK, a citizen of the United States, and a resident of Hollis, in the county of Queens and State of New York, and JOSEPH LEVINE, a citizen of Russia, and a resident of the borough of Brooklyn, county of Kings, city and State of New York, have invented a new and useful Denominating Apparatus, of which the following is a specification.

The invention relates to an apparatus for the use of paymasters for denominating currency for payrolls, or for other purposes, and has for its objects to improve certain details of construction whereby the device will be cheap to construct, easy to assemble, will not easily get out of order, and which will be easy to repair.

These and other objects will more fully appear in the following specification and accompanying drawings considered together or separately.

The invention is illustrated in the accompanying drawings, in which like parts in all of the several figures are designated by similar characters of reference, and in which—

Fig. 1 is a plan view partly in section of an apparatus embodying the invention.

Fig. 2 is a section on the line 2—2 of Fig. 1.

Fig. 3 is a detail sectional view taken on the line indicated by 3—3 of Fig. 1.

Fig. 4 is a longitudinal section, partly in side elevation, taken on the line 4—4 of Fig. 1, and

Fig. 5 is a detail sectional view taken on the line 5—5 of Fig. 4.

In the embodiment of the invention illustrated the apparatus comprises a base 1 on which is mounted a frame comprising a strip of sheet metal 2 having its ends 3 bent up at right angles to form bearings. Between the ends 3 are sheet metal standards 4 riveted or otherwise secured to the member 2. Each of the ends 3 and standards 4 is provided with a U-shaped notch 5 in its upper surface, and such notches are in alignment and form bearings for a shaft 6 which extends longitudinally of the frame.

Carried on the shaft 6 are indicator discs arranged in groups of three. The groups are separated by the standards 4. The discs 7, 8, and 9 of each group indicating respec-

tively units, tens and hundreds respectively 55 carry on their peripheries the designations from "0" to "9" inclusive. Each group may, therefore, designate any number from 1 to 999.

Secured to each disc 7, 8, 9 is a ten tooth 60 ratchet wheel 10. The discs are loosely mounted on the shaft 6 and each group is positioned from each other group, and the end groups from the ends of the shaft, by a collar 11. The collars engage within the 65 notches 5 and form bearings for the shaft 6. Each of the ratchets of the "units" and "tens" discs of each group is provided with a deep tooth 12, and coacting with each group is a spring pressed pawl having three teeth 70 13, 14 and 15 of gradually decreasing length and cooperating respectively with the ratchets of the discs 7, 8 and 9.

The pawl is pivoted in an open rectangular frame 16, there being a separate frame 75 surrounding each group of discs. The frames 16 are separated by the standards 4, and all of said frames are pivoted on a rod 17 which extends longitudinally of the apparatus and through the ends 3 and standards 4. At the end of the frame 16 opposite the pivoted point a spring 18 carried in a socket in the base tends to hold the frame 16 in engagement with the lower sides of the collar on each side of the disc group. 85

Cooperation with each frame and in alignment with the spring 18 is a rod 19 which projects upward through a non-circular opening in a casing 20. The rod 19 is non-circular in cross section and is not secured 90 to the frame 16 but rests thereon. Each rod is provided with a button 21, outside of the casing and each button carries a designation indicating the value of the disc group with which it cooperates. Each rod is 95 guided in the frame as shown at 22, and the lower end of the rod is barbed whereby the same may not be withdrawn from the casing.

When the rod cooperating with the \$1 100 disc group, for example, is depressed the tooth 13 will rotate the "units" disc one tooth when the pressure on the button is released. When the deep tooth of the disc 7 is positioned to be engaged by the tooth 105 13 the tooth 14 will be brought into engagement with the ratchet of the disc 8 and the disc 8 will be rotated one step for

each complete rotation of the disc 7 and similarly the disc 19 will be rotated one step for each complete rotation of the disc 8.

5 In order to prevent overthrow of the discs, a pawl 22 is provided for each disc. The pawls are pivoted on a common rod 23 which extends the entire length of the frame and through the members 3 and 4. Each pawl 10 22 has an arm 24 and each arm is attached to frame 16 of its group by means of a helical spring 25.

One side of the member 2 is turned up as shown at 26 and said turned up portion is 15 provided with a plurality of slots, and the arm 24 of each pawl 22 engages one of said slots whereby the pawls are properly spaced to engage the ratchets of the discs and are 20 prevented from becoming disengaged therefrom.

Pivoted to the inner side of each member 3 and to opposite sides of certain of the members 4 is a keeper 27 each having an inverted U-shaped notch 28. The notches 25 28 are adapted to engage over the collars 11 and complete the bearings of the shaft 6. The upper edge of each keeper is provided with a shallow recess 29.

The top 30 of the casing 20 engages the 30 tops of the keepers and hold them in engagement with the collars 11. The ends of the casing are provided with elongated inverted U-shaped notches which bear upon the end collars, 11, and when the casing is secured in place as by means of screws 31 the parts are securely locked in position. The top 30 is provided with a window 32 over each disc group whereby the numerals on the discs will be disclosed. A strip of glass 40 33 extends the entire length of the casing and rests in the recesses 29 and is retained therein by the engagement of the top 30.

In order to reset the discs the shaft 6 is provided with a triangular groove 34 extending the entire length thereof, and each disc is provided with a pivoted pawl 35 adapted to engage the groove. Each pawl has a section of spring wire coiled around its pivot and one end of the wire bears against 50 the wall of a circular recess 36 in the side of the disc and in which the pawl is located, and the other end of the wire bears against the tail of the pawl. When the shaft is rotated by means of the handle 37 the pawls 55 as the groove 34 comes opposite them, are successively engaged and the discs are all rotated until the character "0" of each of them is disclosed through the windows 32. The recess 36 of each disc is enclosed by 60 means of a cap 38 which will protect the pawl 35 and its spring from injury or disarrangement, and will also act as a washer between the disc and the adjoining collar 11.

The button rods being non-circular will 65 always present the designations on the bot-

tons in proper position. Being unsecured to the frames 16 the casing may be removed by simply removing the screws 31. The burrs on the inner end of the rods will prevent withdrawal of the rods when the casing 70 is removed.

The fact that the springs 18 are unsecured to the frames 16 makes assembling of the device easy, as does the fact that all of the frames are pivoted on a single rod and all 75 of the pawls 22 are pivoted on a single rod.

When the free end of the frame 16 is depressed by the rod 19 to release the pawls 13, 14 and 15 from the ratchets to engage the next teeth, the tension of the springs 25 will 80 be increased thereby causing increased engagement of the pawls 22 with the ratchets at the time that the pawls 13, 14 and 15 are being dragged backwards over them. The springs 25 being of wire are not as likely 85 to break as are leaf springs and are more easily replaceable than are the latter.

To remove the shaft 6 and the discs carried thereby, it is only necessary to remove the casing 20 and the glass 33 and swing the 90 keepers 27 upward as shown in Fig. 5. The shaft may then be removed from the notches 5 without disturbing the relative positions 95 of the discs which are positioned by the collars 11. The said collars also cover the groove 34 except at the points where the groove is engaged by the pawls 35.

In accordance with the provisions of the patent statutes, we have described the principle of our invention together with the 100 apparatus which we now consider to represent the best embodiment thereof; but we desire to have it understood that the apparatus shown is merely illustrative and that the invention may be carried out in 105 other ways.

The invention having been described what is claimed and desired to be secured by Letters Patent, is

1. A device of the character described, 110 comprising a series of aligned standards, there being a notch in each standard, said notches being in alignment, a member pivoted to each standard, there being a notch in each member, said member and standard 115 notches being opposed to form bearings, a shaft mounted in the bearings, and means common to all of the members for retaining the same in position.

2. A device of the character described, 120 comprising a series of aligned standards, there being a notch in each standard, said notches being in alignment, a member pivoted to each standard, there being a notch in each member, there being a recess in each member, said recesses being in alignment, an element resting in the recesses, said member and standard notches being opposed to form 125 bearings, a shaft mounted in the bearings, and means common to all of the members 130

for retaining the members and element in position.

3. A device of the character described, comprising a series of alined standards, 5 there being a notch in each standard, said notches being in alinement, a shaft, a plurality of groups of discs mounted on the shaft, a collar on the shaft between each pair of groups and spacing the same apart, 10 said collars engaging the notches, a keeper having a notch therein pivoted to each standard, said keeper notches each engaging a collar, and means common to all of the keepers for retaining the same in position.
- 15 4. A device of the character described, comprising a support, a shaft rotatably mounted in the support, a plurality of discs rotatably mounted on the shaft, a ratchet-wheel carried by each disc, an open frame 20 pivoted in the support, said frame sur-
- rounding the discs and lying to one side of the shaft, a spring engaging the frame at a point opposite the pivot and tending to normally hold the frame in engagement with the shaft, a series of spring actuated pawls 25 pivoted to the frame and adapted to engage the ratchet-wheels, and manually operated means for depressing the free end of the frame against the tension of the spring whereby when the pressure is released the 30 spring will move the frame and pawls to rotate a disc or discs one tooth.

This specification signed and witnessed this 7th day of March, 1921.

WILLIAM A. COOK.
